INVENTOR,
Henry J. Kasch,
BY
Howard J. Smith,
His ATTORNEY

UNITED STATES PATENT OFFICE.

HENRY J. KASCH, OF DAYTON, OHIO, ASSIGNOR TO THE KURZ-KASCH COMPANY, OF DAYTON, OHIO, A CORPORATION OF OHIO.

INTERCHANGEABLE KNOB FOR DIALS.

Application filed March 24, 1924. Serial No. 701,384.

To all whom it may concern:

Be it known that I, HENRY J. KASCH, a citizen of the United States, residing at Dayton, in the county of Montgomery and State 5 of Ohio, have invented certain new and useful Improvements in Interchangeable Knobs for Dials, of which the following is a specification.

This invention relates to new and useful 10 improvements in knobs for dials, and has particular reference to interchangeable knobs for radio dials.

It is the principal object of my invention to provide knobs of different styles and sizes 15 with means which will adapt any one of them to fit a dial of the same or a different color, so that a knob of the style, size and color desired may be easily attached to the dial.

20 It is another object of my invention to make knobs of the above character out of a molded composition such as bakelite, shellac or a cold molded product.

25 In the accompanying drawings, Figure 1 is a front view of a dial to which a small knob of one style is applied. Figure 2 is a side elevational view of the same. Figure 3 is a cross sectional view thereof taken on the line 3—3 of Figure 1. Figure 4, is a side 30 elevational view of the same dial having attached thereto a larger knob than that shown in the preceding figures. Figure 5 is a front view of the same dial to which a knob of a different style is secured. And Figure 6 is 35 a side elevational view of the same.

Throughout the specification and drawings, similar reference character denote corresponding parts.

40 Referring to the accompanying drawings illustrating my invention, the numeral 1 designates a dial for radio tuning that is made of a molded composition such as bakelite. Formed in the central portion of the dial is a threaded shaft-hole 2. (See Figure 45 3.)

Adapted to be screwed into the hole 2 in the dial is a hub 3 which is externally threaded at its inner end and which at its upper end is molded in an integral hub 4 50 within a hollow tapering knob 5. The knob is so molded from bakelite or a like composition that the hub 4 will project axially from the interior surface of its outer end a

sufficient distance to receive the bushing 3, which contains therein a bore of the diameter 55 required to fit over a variometer, vario coupler or other shaft 6. (See Figure 3.)

The bushing 3 and hub portion 4 of the knob 5 have alined radial holes to receive a screw 7 which is adapted to be screwed into 60 said holes through a hole 8 in the outer wall of the knob that is in alinement with them. This screw is adapted to be screwed through the holes in the bushing 3 and hub portion 4 of the knob into engagement with the shaft 65 6, so that when the knob is turned, it will not only rotate the dial 1, but the said shaft which may be that of a variometer, vario coupler or other device.

Any number of knobs of different styles 70 and sizes may be provided with the means I have just described, so that any desired one of them may be inserted in a dial. For example, one person may wish to use the small knob 5, in which event it may be inserted in the dial 1 as shown in Figures 1, 2 and 3. On the other hand, if it is the desire of a person to employ a large knob 9, it may just as easily be secured to the same 75 dial; or a knob 10 of the style shown in Figures 5 and 6 may be attached to the dial if desired. It is thus possible to make up any number of knobs of different styles and sizes from which one may be selected 80 for ready attachment to a dial that is used 85 for radio or other purposes.

Having described my invention, I claim:

1. The combination with a dial made of a molded composition and having a central threaded shaft-hole, of a knob constructed 90 of a molded composition and having a hollow interior, a hub projecting axially from the inner surface of the outer end of said knob, and a bushing molded in said hub and being exteriorly threaded on its 95 outer end for entrance into the threaded shaft-hole in said dial.

2. The combination with a dial made of a molded composition and having a central threaded shaft-hole, of a knob constructed 100 of a molded composition and having a hollow interior, a hub projecting axially from the inner surface of the outer end of said knob, a bushing molded in said hub and being exteriorly threaded on its outer end 105 for entrance into the threaded shaft-hole

in said dial, the outer wall of said knob and the hub therein having alined radial holes adapted to be brought into alinement with a radial screw hole in said bushing, a shaft over which the latter is fitted, and a screw adapted to be forced through the alined holes in the knob and the hole in the bush-

ing, for engagement with said shaft, for the purpose specified.

In testimony whereof I have hereunto set my hand this 22d day of March, 1924.

HENRY J. KASCH.

Witness:

HOWARD S. SMITH.
